UNITED STATES PATENT OFFICE.

HENRY RAUBITSCHEK, OF BROOKLYN, NEW YORK, ASSIGNOR TO ROYAL METAL FURNITURE COMPANY, OF BROOKLYN, NEW YORK, A CORPORATION OF NEW YORK.

DESIGN FOR A FRAME FOR BEDSTEAD ENDS.

SPECIFICATION forming part of Design No. 35,881, dated April 22, 1902.

Application filed March 13, 1902. Serial No. 98,114. Term of patent 7 years.

To all whom it may concern:

Be it known that I, HENRY RAUBITSCHEK, a citizen of the United States, residing in the borough of Brooklyn, county of Kings, city 5 and State of New York, have invented and produced a certain new, useful, and original Design for Frames for Bedstead Ends, of which the following is a specification.

In the accompanying drawing I have shown 10 a frame for bedstead ends in which my design is embodied.

In the drawing, *a b* indicate the side bars terminating in feet *c*.

d e indicate the top and bottom cross-bars of the frame. 15

The frame is ornamented at the top by top ornaments *f*, which are surmounted by a cross-bar *g*.

What I claim is—

The design for a frame for bedstead ends 20 substantially as herein shown and described.

H. RAUBITSCHEK.
